UNITED STATES PATENT OFFICE.

WILLIAM F. ROTHE, OF EAST ST. LOUIS, ILLINOIS, ASSIGNOR TO WM. F. ROTHE AND COMPANY, OF EAST ST. LOUIS, ILLINOIS, A CORPORATION OF ILLINOIS.

CARBURETER.

997,417.

Specification of Letters Patent. Patented July 11, 1911.

Application filed February 21, 1910. Serial No. 544,991.

To all whom it may concern:

Be it known that I, WILLIAM F. ROTHE, a citizen of the United States, and a resident of the city of East St. Louis, county 5 of St. Clair, and State of Illinois, have invented a new and useful Improvement in Carbureters, of which the following is a specification.

This invention relates to carbureters.

10 It has for its principal objects to secure a positive correlated action of the air inlet valve and the oil inlet valve, to provide for a variable and proportional correlation between the two valves, to provide for the 15 thorough mixture of the air and vapor, and to attain certain other advantages herein-after more fully appearing.

The invention consists in the parts and in the arrangements and combinations of 20 parts hereinafter described and claimed.

In the accompanying drawings which form part of this specification and wherein like symbols refer to like parts wherever they occur, Figure 1 is a vertical section 25 through the casing of the carbureter showing the air and oil inlet valves, respectively, in closed position and the throttle valve in opened position; Fig. 2 is a top plan view of the carbureter; Fig. 3 is a detail view of 30 the lever which is interposed between the air inlet valve and the oil inlet valve; and Fig. 4 is a fragmentary section of a modification of the air valve.

The carbureter comprises a hollow casing 35 or shell 1. In the bottom portion of the casing 1 is a mixing chamber 2 which is connected by an upturned passageway 3 to a spiral passageway 4. The passageway 4 is preferably equipped with a triple bladed 40 spiral 5, whereby the air and vapor is caused to travel in a whirling motion through the same, so that it is thoroughly mixed before it leaves the outlet opening 6. The outlet opening is controlled by a "butterfly" valve 45 or circular disk valve 7 which is mounted on a rock-shaft 8 extending transversely of the outlet passageway. On the end of the rock-shaft 8 is a lever arm 9 which may be connected in any suitable manner to a manipulating device, not shown.

A discharge nozzle 10 projects into the mixing chamber 2 through an opening in the bottom of the casing 1. The outer end portion of this nozzle member is screw-threaded

or otherwise suitably arranged for connection with an oil supply pipe, not shown. Extending in vertical alinement with the nozzle 10 is an elongated needle-valve member 11 whose lower end portion is slidably fitted through a guide opening in a horizontal partition 12 within the casing. The upper end portion of the needle-valve member 11 is slidably fitted in a central bore 13 in a screw-plug 14 which is secured in a screw-threaded opening in the top of the casing 1. The upper portion of the bore 13 is screw-threaded to receive a screw-stud or adjustable limiting stop 15. This screw-stud or stop member 15 is provided with a transverse handle portion 16 whereby the same 55 may be conveniently manipulated and adjusted; and a lock nut 17 is also provided on said screw-stud whereby the same may be locked in its adjusted position. On the lower portion of the needle-valve member 11 is fixed a collar 18 and on the upper portion of said member 11 is fixed a second collar 19. Sleeved loosely on the needle-valve member 11 is a collar 20 and also sleeved on said member 11 is a coil spring 21 which 60 is interposed between said loose collar 20 and the upper fixed collar 19. The loose collar 20 is provided with oppositely projecting trunnions 22 which are fitted in slots 23 in the ends or forks 24 of a rocking lever 25. This rocking lever 25 is pivotally mounted on a rod 26 which extends transversely of the casing 1. The rocking lever 25 may obviously be made of a casting having forked or bifurcated end portions or 65 the same may be blanked and formed from a single piece of sheet metal substantially as shown.

The air inlet opening 27 is provided in the top of the casing 1 at the end opposite to the outlet opening 6. In the inlet opening is fitted a screw-threaded sleeve 28 and the casing is preferably split and provided with a pair of lugs 29 which are perforated to receive a clamping bolt 30 whereby said sleeve 28 is securely held in position. A circular disk valve 31 cooperates with the inner end of said annular member or sleeve 28 and it is secured tightly to an elongated stem or rod 32. The upper end portion of this rod 32 is slidably fitted in an axial bore in the central or hub portion 33 which is connected by a spider or radial members 34 to the

sleeve 28. The lower end portion of said valve-stem 32 is slidably fitted in an axial bore 35 in a screw-plug 36 which is fitted in a screw-threaded opening in the bottom of 5 the casing 1. The lower portion of the bore 35 in said plug 36 is screw-threaded to receive a screw-threaded stud or limiting stop member 37. This member 37 is similar to the member 15 in the screw-plug 14 for the 10 needle-valve and it is locked in its adjusted position by a jam nut 38. The screw-plug 36 is also adapted to be adjusted longitudinally and it is locked in position by a jam nut 39. Sleeved loosely on the stem 32 adjacent 15 to the valve 31 is a collar 40. This collar 40 is provided with oppositely extending trunnions 41 which are fitted in slots 42 in the end portions or forks 43 of the rocking lever 25. Sleeved on the valve-stem 32 between 20 said collar 40 and the inner end of the screw-plug 36 or, preferably, an interposed collar 44, is a coil spring 45 whereby the end portions 43 of the lever 25 are held in contact with the valve 31 to resiliently 25 support the same in raised position, in normal coöperative relation with the inner end of the sleeve 28. By moving the screw-plug 36 inwardly or outwardly, the tension of 30 said spring 45 may be varied. Obviously, the collar 40 may be fixed to the stem 32, if desired, in which case the end of the lever need not bear against the under side of the valve 31. Normally, the valve 31 does not entirely close the inlet opening 27 but its 35 peripheral portion which coöperates with the inner end of said sleeve 28 is spaced slightly therefrom. The needle-valve 11 when fully closed or seated on the nozzle 10 constitutes, in effect, the stop which limits 40 the uppermost normal position of said valve 31. That is, the rocking lever 25 being pivotally connected at one end to the collar 40, the spring 45 will tilt the lever and raise the valve 31 until the opposite end portion 45 of the lever 25 which is pivotally connected to the loose collar 20 on the needle-valve 11 bears against the upper side of the fixed collar 18 on said needle-valve, the parts being so proportioned that the spaced position 50 of the air valve is thus controlled. The sleeve 28 may be also adjusted inwardly or outwardly, as desired.

The proportional opening of the needle-valve and the air valve is controlled by the 55 adjustable screw-studs or stops 15 and 37 and numerous adjustments may be effected by manipulating the same. The spring 21 which is sleeved on the needle-valve 11 is of sufficient strength to lift said needle-valve 60 when the loose collar 20 is raised by the rocking lever 25. This spring 21 is, however, weaker than the spring 45 which acts upon the air valve 31. By this arrangement the stop member 15 may be adjusted so that 65 the needle-valve 11 has but a very slight up-

ward movement and the stop 37 may be adjusted so that the air valve 31 has considerable downward movement, as the spring 21 will yield when the needle-valve is arrested by its stop and permit of the continued 70 movement of the rocking lever until the stem 32 is arrested by its stop.

In the operation of the carbureter, the outlet or throttle valve 7 is opened and the suction stroke of the engine draws the air into 75 the casing 1 through the inlet opening 27. The valve 31 is thereby drawn downward against the tension of the spring 45. The valve being secured to the stem 32 and bearing upon the end of the rocking lever 25, or 80 the collar 41 being secured to the stem, as the case may be, the lever 25 is rocked and the loose collar 20 on the needle-valve stem 11 is raised. The spring 21 raises the needle-valve 11 until it contacts with the stop 15. 85 When the stem of the needle-valve contacts with the stop 15, the spring 21 will yield and permit the air valve 31 to continue its downward movement until the stem 32 contacts with the stop 37. After the engine is 90 started, the valves may be adjusted to produce the required mixture.

The air valve 31 is provided with a central opening 46 which is normally closed by an outwardly opening relief valve 47. This 95 relief valve 47 is sleeved loosely on the upper portion of the stem 32 and is resiliently held to its seat by a spring 48 which is sleeved on said stem 32 above said relief valve and adapted to bear against the hub 100 portion 33 when the air valve is in its uppermost position. This relief valve 47 is provided as a "blow back" valve to release the pressure in case of "back fires."

To insure the opening of the air valve, 105 its peripheral portion is cut away annularly to provide an upper portion 49 of reduced diameter which fits loosely within the sleeve 28 and an annular shoulder or flange 50 below said reduced portion which underlies 110 the inner end of said sleeve 28. The upper face of this annular shoulder or flange 50 may be flat and at right angles to the peripheral face of the reduced portion 49 but it is preferably grooved as shown in Figs. 1 and 4; and the inner end of the sleeve 28 is beveled to correspond to the inclined face of the shoulder as shown in Fig. 1 or it is rounded to correspond to the curvature of the concavity or groove 51 in the shoulder 50 illustrated in Fig. 4. By this arrangement, the direct downward movement of the inrushing air is broken and the air is deflected laterally and upwardly against the inner end of the sleeve 28 and the surrounding portion of the casing whereby the downward movement of the air valve is made 115 more positive.

Obviously, the device admits of considerable modification without departing from 120

my invention. Therefore, I do not wish to be limited to the specific construction and arrangement shown.

What I claim is:

5. 1. A carbureter comprising a hollow casting having a mixing chamber in the bottom thereof, an air inlet passage leading to said mixing chamber, an outlet passage leading from said mixing chamber, a throttle valve 10 arranged to control the outlet of the mixed air and oil, a valve arranged to control the air inlet; an oil nozzle arranged to discharge into said mixing chamber, a valve arranged to control the discharge from said oil nozzle, 15 a resilient working connection between said air valve and said oil valve whereby said valves are simultaneously actuated, an adjustable stop for varying the opening limit of said oil valve, and an adjustable stop for 20 proportionately varying the limit of the opening of said air valve with respect to the oil valve.
2. A carbureter comprising a hollow casting having a mixing chamber in the bottom 25 thereof, an air inlet passage leading to said mixing chamber, and an outlet passage arranged to conduct mixed air and oil from said mixing chamber, an oil nozzle arranged to discharge into said mixing chamber, a 30 needle-valve arranged to control the discharge from said oil nozzle, an adjustable stop for limiting the stroke of said needle-valve, an inwardly opening valve arranged to control the air inlet, an adjustable stop for 35 limiting the movement of said air valve, a rocking lever operatively connected to said air valve so as to be actuated thereby, said rocking lever being resiliently connected to said needle-valve whereby the latter is 40 simultaneously actuated with said air valve.
3. A carbureter comprising a casing having a mixing chamber therein, an air inlet passage leading to said mixing chamber, and an outlet passage arranged to conduct 45 mixed air and oil from said mixing chamber, an oil nozzle arranged to discharge into said mixing chamber, a needle-valve arranged to control the discharge from said oil nozzle, an adjustable stop arranged to 50 limit the opening movement of said needle-valve, an inwardly opening valve arranged to control the air inlet, an adjustable device arranged to limit the opening movement of 55 said air valve, a working connection between said needle-valve and said air valve whereby the needle-valve is actuated simultaneously with the actuation of said air valve, said air valve having a passage therethrough, and an outwardly opening relief valve arranged to normally close said passage.
4. A carbureter comprising a casing having a mixing chamber therein, an air inlet passage leading to said mixing chamber, an oil nozzle arranged to discharge into said 65 mixing chamber, a valve arranged to control the discharge from said oil nozzle, an inwardly opening valve arranged to control the air inlet, said air valve having a portion of reduced diameter which is adapted to normally fit loosely within the air inlet 70 passage and also having an annular shoulder arranged to extend beyond the sides of the inlet passage at the inner end thereof.
5. A carbureter comprising a casing having a mixing chamber therein, an air inlet 75 passage communicating with said mixing chamber, an oil nozzle arranged to discharge into said mixing chamber, a valve arranged to control the discharge from said oil nozzle, an inwardly opening valve arranged to control the air inlet, said air valve having a portion of reduced diameter which is adapted to normally fit loosely within the air inlet passage, and also having an annular shoulder which extends beyond 80 the peripheral side face of said reduced portion and having its outer face grooved, and a counterpart portion at the inner end of said air inlet passage which co-operates with the grooved portion of said annular shoulder on the air valve.
6. A carbureter comprising a hollow casting having a mixing chamber therein, an air inlet passage which communicates with said mixing chamber, and an outlet passage which is arranged to conduct mixed air and oil from said mixing chamber, means for supplying oil to said mixing chamber, and an inwardly opening valve arranged to control the air inlet, said valve being resiliently 95 held in normal position and having a portion of reduced diameter which normally fits loosely within the air inlet passage and also having an annular shoulder which extends beyond the peripheral side face of said reduced portion, the outer face of said annular shoulder being grooved annularly, and a counterpart annular portion at the inner end of said air inlet passage in co-operative relation to said annular shoulder on said valve.
7. A carbureter comprising a hollow casting having a mixing chamber therein, and means for supplying oil to said mixing chamber, said casing having an air inlet opening which communicates with said mixing chamber, a sleeve secured in said air inlet opening, and an inwardly opening valve arranged to co-operate with the inner end portion of said sleeve to control the air inlet, said valve having a portion of reduced diameter adapted to fit loosely within said sleeve and also having an annular shoulder extending beyond the peripheral side face of said reduced portion and overlapping the inner end of said sleeve.
8. A carbureter comprising a hollow casting having a mixing chamber therein, and means for supplying oil to said mixing chamber, said casing having an air inlet opening which communicates with said mix-

- ing chamber, a sleeve secured in said air inlet opening, and an inwardly opening valve arranged to coöperate with the inner end portion of said sleeve to control the air inlet, 5 said valve having a portion of reduced diameter which is adapted to fit loosely within said sleeve and also having an annular shoulder extending beyond the peripheral side face of said reduced portion and overlapping the inner end of said sleeve, the face of said shoulder which coöperates with the end of the sleeve being grooved annularly as a counterpart of the end of said sleeve.
9. A carbureter comprising a hollow casting having a mixing chamber therein, an air inlet passage communicating with said mixing chamber, and an outlet passage arranged to conduct mixed air and oil from said mixing chamber, an oil nozzle arranged to discharge into said mixing chamber, a reciprocatory needle-valve arranged to control the discharge from said oil nozzle, an adjustable device for limiting the opening movement of said needle-valve, a rocking lever operatively connected with said needle-valve whereby the said needle-valve is moved positively into closed position when the rocking lever is moved in one direction and whereby, also, said rocking lever is permitted to continue its movement in the opposite direction after said needle-valve has reached the limit of its opening movement, and an inwardly opening valve arranged to control the air inlet, a spring arranged to yieldingly hold said air valve in normal position, an adjustable device for limiting the opening movement of said air valve, and an operative connection between said air valve and said rocking lever whereby the opening and closing movements of said air valve and needle-valve are simultaneous.
10. A carbureter comprising a casing hav-
- ing an air inlet opening therein, and an inwardly opening disk valve arranged to control the air inlet, said valve having a portion ⁴⁵ of reduced diameter which is adapted to fit loosely within said air inlet opening and also having an annular flange portion projecting beyond the peripheral face of said reduced portion, the outer face of said annular flange ⁵⁰ being grooved annularly, and an annular counterpart portion at the inner end of said inlet opening in coöperative relation to said annularly grooved flange on said valve.
11. A carbureter comprising a casing having an air inlet opening therein, a sleeve adjustably secured in said air inlet opening, and an inwardly opening disk valve arranged to coöperate with the inner end portion of said sleeve to control the air inlet, ⁶⁰ said valve having a portion of reduced diameter which is adapted to loosely fit within said sleeve and also having an annular flange portion which projects beyond the peripheral face of said reduced portion and overlaps the inner end of said sleeve, the outer face of said annular flange being grooved annularly and the inner end of said sleeve being a counterpart of said annular groove. ⁶⁵
12. A carbureter comprising a hollow casting having an air inlet opening therein, an inwardly opening disk valve arranged to control the air inlet, said valve having a portion of reduced diameter adapted to fit loosely within the air inlet opening and an annular portion arranged to overlap the inlet opening. ⁷⁰

Signed at St. Louis, Missouri, this 16th day of February, 1910.
